VIBRATORY CONTACT DEVICE

Emile C. Guedon, Audubon, N. J., assignor to
 Radio Corporation of America, a corporation
 of Delaware

Application August 31, 1935, Serial No. 38,739

6 Claims. (Cl. 200—90)

The present invention relates to vibratory contact devices, and more particularly relates to vibratory electrical contact devices of the type adapted to control or function in power supply circuits in connection with radio receiving apparatus and the like for vehicles. Such devices are commonly known as vibrators.

For use with radio receivers, devices of this character are employed in potential changers and adapted rapidly to make and break electrical circuits in connection with a step-up transformer and in connection with a low voltage battery such as an automobile storage battery, to produce an alternating current or a rectified current at a higher potential for the anode circuits and the like. The operation of such devices involves the mechanical operation of a vibratory reed or armature and the interrupting or opening and closing of electrical circuits, which tend to produce undesirable sound and electrical disturbances in connection with the operation of radio apparatus.

Vibratory contact devices are now extensively used in connection with potential changer systems for automobile radio receivers and are usually encased in metallic shields which tend to prevent electrical disturbances from being radiated thereby and to reduce the noise of operation.

Such devices, while requiring closed shields and sound proof containers, require inspection and adjustment, and it is an object of the present invention to provide an improved vibratory contact device which may readily be assembled in manufacture and opened for inspection and adjustment while, at the same time, it is effectively electrically shielded and quiet in operation.

It is also an object of the present invention to provide an electrical vibrator or interrupter unit having an improved arrangement of operating elements and an improved mounting means therefor in a shielded container, whereby said device is prevented from radiating electrical disturbance and mechanical noise.

It is a further object of the present invention to provide in a shielded container an improved mounting means for an electrical vibrator or vibratory contact device which permits the vibrator elements to be electrically insulated and spaced from the walls of the container while the vibrator unit is releasably mounted resiliently in the container without permanent fastening means.

The invention will, however, be better understood from the following description when considered in connection with the accompanying

drawing and its scope will be pointed out in the appended claims.

In the drawing, Fig. 1 is a cross-sectional view substantially full size of an electrical interrupter or vibratory contact device embodying the invention;

Fig. 2 is a similar cross-sectional view of the device of Fig. 1 drawn on the lines 2—2 of Fig. 1;

Fig. 3 is an end view also on the same scale as Figs. 1 and 2 taken on the line 3—3 of Fig. 2; and

Fig. 4 is a schematic circuit diagram of electrical connections for the device of Figs. 1, 2 and 3 in connection with voltage transforming means of a potential changer system for a low voltage source of power supply, to provide high voltage alternating current or direct current.

Referring to Figs. 1, 2 and 3, a metallic casing is provided comprising a shallow cup-shaped rectangular base 5 into which is seated the open end of an elongated rectangular can 7 to provide a closed container. The base and can are of conducting material such as sheet metal and may be constructed of sheet metal parts welded or otherwise secured together as indicated more clearly in Fig. 3. In this case, a U-shaped member providing the end wall 9 (Fig. 2), and the side walls 11, is engaged along its edges by two channel members 13 forming the front and rear walls of the container. These parts are preferably welded together. The base and the can members are held in interlocking engagement with each other by the flange of the base and by suitable means such as short threaded studs 15 provided with clamping nuts 17, as shown in Figs. 1 and 2, the studs being carried by the inner walls of the can member and welded thereto as indicated at 19 (Fig. 1) with the ends projecting through the base.

The base is also provided with a central opening 21 in which are mounted socket prongs or terminals 23 on a strip of insulating material 25 carried by the base on the inner face thereof as shown in Figs. 1 and 2. By the provision of the prong base, the vibrator device is adapted to be mounted in connection with any suitable socket means (not shown) and adapted to engage the socket terminals. The prong base forms part of the casing and serves to close the opening 21.

The base and can together, form an outer metallic shell providing an electrical shield and a closed container adapted to prevent the transmission of sound therefrom. To aid in the sound

insulation, the shell or casing is of relatively large size with respect to the vibrator unit to be enclosed thereby and is provided with an inner lining or sound isolating casing of resilient material such as sponge rubber, comprising a hollow block 27 of such material mounted in the can and a solid block or layer 29 of the same or similar resilient material adapted to close the open end of the hollow block and the open end 10 of the can as indicated in Figs. 1 and 2.

The inner face of the block or layer 29 of resilient material is slotted as indicated at 31 and the inner side walls of the hollow block are similarly slotted as shown more particularly in Figs. 1 and 3 at 33 to receive three of the edges of a flat thin plate of insulating material 35 on which the vibrator operating elements are mounted as a unit.

When the vibrator device is mounted in vertical position with the prongs down, the mounting plate stands in a vertical position in the slots thereby being resiliently mounted with respect to the outer shell by the inner casing or envelope. The vibrator or interrupter unit is therefore held 25 by its edges and with the parts thereon as shown in spaced relation to the inner walls of the casing.

The plate 35 is a combined insulating and mounting plate for the vibrator parts or elements which may comprise an operating electromagnet 37 secured to one face of the plate 35 and an armature member 39 arranged to be attracted thereby and comprising a bar mounted on a short flat spring 41 which is secured to the armature and to one end of the magnet 37 by screws indicated at 43, Fig. 2. The armature is provided with a contact arm 45 which extends upwardly through a slot 47 and between two adjustable contacts 49 and 51 carried by elongated pivoted arms 53. The arms 53 are insulated from each other and are mounted on the plate 35 by a pivot bolt 55. A lower contact arm 57 is also provided on the armature and operates in conjunction with an adjustable contact 59 carried by a pivoted arm 61 similar to the arms 53 and having a pivot bolt 63 corresponding to the bolt 55.

The armature extension 45 carries a contact 65 which moves with the armature between the adjustable contacts 49 and 51. The lower contact 59 and the upper contacts 49 and 51 are adjusted by moving the arms 53 and 61 about the pivot bolts until the air gap is so adjusted that the contact 59 makes and breaks properly with a contact 67 on the arm 57 to energize and de-energize the magnet thereby causing the armature to vibrate, and the contact 65 to make and break evenly with the contacts 49 and 51. The arms 53 and 61 are then clamped into position by the bolts 69 and 71.

The operating elements are thus mounted on 60 opposite sides and in balanced relation to a rectangular flat plate of insulating material forming a single mounting and insulating member therefor which, in turn, is resiliently gripped along its edges by an inner casing of resilient material 65 having slots for positioning the plate thereby to space the operating elements of the device between the inner walls. An outer closed casing of 70 conducting material is provided and both the inner and outer casings being adapted to be opened for inspection of the vibrator unit.

It will be seen that by opening the casing and removing the block 29, the vibrator unit may be withdrawn from the hollow container and inspected without breaking the flexible connection 75 leads 22 with the terminals 23, several of such

connections being omitted from the drawing for the sake of simplifying the same and being shown more clearly in the potential changer circuit diagram of Fig. 4 to which attention is now directed.

In Fig. 4 the same reference numerals are used 5 to designate the corresponding parts of Figs. 1, 2 and 3. The vibrator casing is indicated by the circle 13 and contains the operating electromagnet 37, the armature 39 and the contacts 49 and 51 associated with the armature. The lower arm 10 is shown at 57 with the operative contact 59 adjacent thereto.

The operating coil 57 is connected to the contact 59 through a lead 15 and to a terminal prong 17 which is connected through a lead 79 with a 15 center tap 81 on the primary 83 of a step-up transformer 85. The lead 79 is also connected with a positive supply lead 87 of a low voltage source of operating potential.

The contacts 49 and 51 are connected through 20 leads 89 with terminal prongs 91, which, in turn, are connected to the leads 93 with the terminals 95 of the primary winding 83. The armature is connected to a terminal prong 97 and to a negative supply lead 99 of the low voltage supply 25 source, which is grounded as indicated at 101 and connected with an output lead 103. The terminal or socket prongs 11, 91 and 97 are provided with suitable receptive jacks or terminals 102. The lower arm 51 is connected with the 30 armature electrically as indicated and is closed with the contact 59, whereby the operating electromagnet 37 is energized from the supply source causing the armature to move toward the electromagnet, breaking contact with the contact 35 51 and engaging with the contact 49. The armature under spring action is returned upon breaking of the contact 59 which de-energizes the electro-magnet 37, and assumes the position shown, when the action is repeated. 40

Through operation of the armature in connection with the contacts 49 and 51, each half of the primary winding 83 is alternately energized from the low voltage supply source causing an alternating potential to appear on the terminals 105 45 of the secondary 107. This alternating potential may be supplied to any suitable load (not shown) through output leads 109. Additional contacts 111 associated with the armature in the same manner as the contacts 49 and 51 may be connected as indicated by the dotted connections 113 to rectify the secondary voltage in connection with the terminals 105, and the rectified current may be taken through a supply lead 115 connected to a center tap 117 on the secondary and 50 the low voltage output lead 103.

Since the operation and circuits in connection with vibratory contact devices for power supply are known and understood, further description is believed to be unnecessary. 60

It will be seen, however, that the device as shown and described provides effective shielding for the operating parts and, since the outer casing is of metal, it may be grounded as indicated at 118 to conduct stray currents directly to ground. 65

The relatively thick internal casing comprising two separable portions serves to provide additional effective sound insulation and resiliently to hold the vibrator unit in a predetermined position in spaced relation to the internal walls without additional fastening means other than the simple slot in at least two of the walls of the internal casing to engage it along the edges of the mount- 70

ing plate. The device is, therefore, readily assembled in manufacture and may be easily opened for inspection and adjustment.

The hollow interior container having a single open end closed by a flat block of resilient material tends to provide a resilient lining of low cost and one which is easily assembled since the flat block 29 enters the end of the outer shell and seats on the end of the vibrator mounting plate. The interior lining is then held slightly in compression by the base which is clamped against and around the open end of the outer can.

The device is adapted to operate as a potential changer with low voltage direct current as a source of power supply to provide anode and other "B" potentials for an automobile radio receiver. The device provides a removable mechanical interrupter unit resiliently mounted without additional holding means in a slot in the interior walls of the electrical shield and sound proof container. The outer shield provides good electrical conductivity whereby it may be grounded and encloses the sound isolated magnetic interrupter.

I claim as my invention:

1. An electrical vibrator device comprising, in combination, a metallic casing having separable portions interengaging to provide a closed electrical shield and container, means providing inner walls for said casing of resilient material, certain of said walls being recessed, and an electrical vibrator mechanism having portions engaging said walls within the recesses to hold said unit in spaced relation to the interior of said casing, said recesses and walls forming the sole supporting and positioning means for said mechanism.

2. An electrical vibrator device comprising, in combination, an electrical shield casing, means providing resilient interior walls for said casing having two spaced elongated slots, a plate member extending across the interior of said casing and having edges engaging in said slots, and an electrical vibrator mechanism mounted on said plate in spaced relation to the interior walls of said casing.

3. An electrical vibrator device comprising, in combination, an electrical shield casing, means providing resilient interior walls for said casing having two spaced elongated slots, a plate member extending across the interior of said casing and having edges engaging in said slots and an electrical vibrator mechanism mounted on said plate in spaced relation to the interior walls of said casing, said first named means comprising an interior casing having separable portions cor-

responding to the separable portions of said outer casing.

4. A vibratory contact device comprising, in combination, an outer metallic shell providing an electrical shield and including two separable portions, one which is an elongated open ended can, an inner casing for said shell comprising a hollow block of resilient material seated in said can and having an open end adjacent the open end of the can, a block of resilient material adapted to seat against the open end of said inner casing and to close the open end of said can, a slot in at least two of the walls of said inner casing, and a vibrator unit mounted in said inner casing and comprising a flat plate engaging the slots in the inner walls thereof, whereby said vibrator unit is mounted in spaced relation to said walls and is resiliently supported within said outer metallic shell.

5. A vibratory contact device comprising, in combination, an outer metallic shell providing an electrical shield and including two separable portions, one which is an elongated open ended can, an inner casing for said shell comprising a hollow block of resilient material seated in said can and having an open end adjacent the open end of the can, a block of resilient material adapted to seat against the open end of said inner casing and to close the open end of said can, a slot in at least two of the walls of said inner casing, and a vibrator unit mounted in said inner casing and comprising a flat plate engaging the slots in the inner walls thereof, whereby said vibrator unit is mounted in spaced relation to said walls and is resiliently supported with said outer metallic shell, insulated socketed terminals projecting from said outer shell and adapted to be connected with said vibrator unit, whereby said device is detachable from an electrical circuit.

6. In a potential changer system operable with a low voltage direct current source and supplying high voltage operating potentials for radio receiving apparatus and the like, a vibrator device comprising an outer shell of conducting material providing a closed container, an inner casing for said shell of resilient material providing slotted spaced inner walls, an electrical vibrator unit mounted in said inner casing and having edges engaging the slots in said inner walls to hold the operating elements thereof in spaced relation to said inner casing, and means providing insulated electrical contact prongs for said vibrator unit extending exteriorly of the outer shell.

EMILE C. GUEDON.
